AUDION AMPLIFIER

Frederick H. Drake, Boonton, N. J., assignor, by
mesne assignments, to Radio Corporation of
America, New York, N. Y., a corporation of
Delaware

Application February 6, 1931. Serial No. 513,993

6 Claims. (Cl. 250—14)

This invention relates to audion amplifiers, and more particularly to amplifiers which include interstage coupling impedances designed for ready removal, and replacement by similar impedances of different magnitude, to permit operation over different frequency bands.

One conventional method employed in adapting a radio receiver for use at different frequency bands involves the substitution of coil assemblies which form part of the interstage couplings in a tuned radio frequency amplifier. When high sensitivity is desired, there may be several tuned stages, thus increasing the number of interchangeable parts which must be kept at hand, and increasing the time and work required to shift from one frequency range to another. Furthermore, this increase in the number of parts which must be changed raises a possibility that the amplifier may be rendered substantially inoperative by failure to make appropriate changes in all of the removable circuit elements.

The desirability of a simpler system for changing the frequency range in radio receivers has been recognized but previous attempts to avoid the changing of a number of separate units have been unsatisfactory. In particular, it has been considered impractical to construct all of the replaceable elements of one frequency range as a single assembly which could be connected to or removed from the receiver chassis as a single unit. With one particular receiver in which the radio frequency transformers were mounted within individual shields or "coil cans", the receiver operation was unstable when all of the coil cans were secured to a plate to constitute a single unit.

From a theoretical consideration of the problem, it was assumed that some new electrical couplings were established by mounting the coil cans upon a single supporting plate, since this step altered the operation of the receiver. According to the known design practice, it was believed that such incidental couplings could be avoided by grounding all of the coil cans upon each other, either through the supporting plate itself, or by additional low resistance connections. In actual practice, however, the operating characteristics of the amplifier were still affected even though the coil cans were carefully grounded to their supporting plate, and attempts to construct unit or gang coil assemblies were abandoned under the belief that the mechanical interconnection of the separate units resulted in unstable operation even though no new electrical couplings were established by the mechanical coupling of the units in a single assembly.

According to the present invention, stable operation is obtained, while employing ganged coil or transformer elements by so constructing the assembly that the mechanical interconnection of the parts does not give rise to the establishment of electrical couplings between the coils or transformers. I have found that the mechanical interconnection of a plurality of coil cans, each individually grounded upon the amplifier chassis, will not affect the electrical operation of the amplifier when care is taken to avoid the grounding of the coil cans upon the connecting or supporting plate.

An object of the invention is to provide a multi-stage tuned amplifier of the type having interstage coupling impedances which are removable as a single unit, and in which the performance of the amplifier is substantially unaffected by the mechanical interconnection of the coupling impedances. A further object is to provide an amplifier of the type stated, in which the coupling impedances are coils mounted within shielding cans, and the mechanical assembly of the coils is effected by securing the cans to, but insulating the same from, a metal plate. Further specific objects relate to the provision of novel forms of shielding cans, and assemblies of shielding cans.

These and other objects of the invention will be apparent from the following specification, when taken with the accompanying drawings, in which,

Fig. 1 is a side view, with parts broken away, of a radio receiver,

Fig. 2 is an enlarged plan view of a coil form 90 and the shield cap upon which it is mounted, a diagram of associated circuit elements being superposed upon the view of the coil form,

Fig. 3 is an enlarged fragmentary view, in perspective, of the top of one of the coil assembly 95 shields,

Figs. 4 and 5 are an inside plan and an elevation, respectively, of the removable coil assembly, and

Fig. 6 is an enlarged section of a portion of the 100 coil assembly.

In the drawings, the reference numeral 1 identifies the outer casing of a radio receiver which includes a plurality of stages of tuned radio frequency amplification, the particular 105 receiver illustrated in Fig. 1, being of the type described and claimed in the copending application of John E. Johanson, Ser. No. 513,999 filed February 6, 1931. As described in the Johanson application, one wall of the receiver casing is pro- 110

vided with an opening 2 which permits access to the space to be occupied by inductances or transformers which, with the several sections of a gang condenser 3, provide the tuned interstage 5 couplings of the radio frequency stages. A plate 4 of insulating material carries groups of expandable or frictional terminals 5 which engage socket terminals on the removable coil elements to effect the desired electrical connections when 10 the coils are assembled on the receiver chassis, one such group of terminals being shown at the left side of Fig. 1. The opening 2 in the wall of the receiver is closed by a metal cover plate 6 which has a handle 7, for convenience of manipulation, and is provided with sliding latches 8 which engage pins 9 to secure the cover to the receiver casing.

The general construction of the interchangeable coils and their shielding cans may follow 20 the usual design practice. As illustrated, a coil form 10 of insulating material is secured to a metal cap or base 11 by a plurality of studs 12 which are fixed in the coil base 13 and riveted to the cap 11. As shown diagrammatically in 25 Fig. 2, the electrical structure of the interchangeable unit may be that of a transformer, having a primary P and secondary S, which is wound upon the cylindrical portion 10 of the coil form.

The respective windings are connected between 30 tubular or socket terminals 14 that extend through the base 13 of the coil form. When the coil unit is plugged into the receiver, by fitting the socket terminals 14 over the pin terminals 5 of the receiver, circuit connections as illustrated 35 in Fig. 2 are established, i. e., the primary winding P is connected between the plate of the amplifier tube 15 and a lead 16 which extends to the source of plate current supply, the lead being by-passed for radio frequencies by a condenser 40 17. The secondary winding S is connected between ground and the control grid of the succeeding tube 18, which may be another amplifying tube or the detector. The condenser unit 3 is permanently connected between the control grid 45 and the ground, i. e., a point on the chassis of the receiver, and constitutes the adjustable tuning element of the interstage coupling. One of the studs 12 is connected, by a jumper 19, to the grounded terminal 14 of the secondary S, thus 50 grounding the shield cap 11 upon the chassis.

The shielding of the individual coil elements is completed by the cylindrical boxes or "coil cans" 20 which fit within and are secured to the caps 11. As best shown in Fig. 3, a plurality of internally threaded rivets 21 are secured to the 55 ends of the coil cans, the heads of the rivets being insulated from the can by plates 22, 23, of insulating material and the shanks of the rivets are spaced from the coil can top by washers 24.

All of the coil elements are mounted upon the 60 cover plate 6 by screws 25 which are threaded into the rivets 21 of the coil cans. As shown in Fig. 6, the washers 24 are preferably of slightly greater thickness than the end wall of the coil can, thus facilitating the fitting of the groups of 65 coil terminals 14 upon the stationary pin terminals 5 by permitting the individual coil cans to have a slight tilting movement with respect to the cover plate 6. The cap 11 is provided with 70 apertures 26 which are of appreciably larger diameter than the pin terminals 4, thus preventing inadvertent shorting of the tube circuits when the coil assembly is applied to or removed from the receiver without first opening the supply cir- 75 cuits.

While the invention has been described in connection with a radio receiver of the tuned radio frequency amplification type, it will be apparent that it is not limited in its application to any one type of amplifier. The same principles apply equally well in the construction of other tuned or untuned amplifiers which are adapted for operation over different frequency ranges by removable interstage coupling impedances.

I claim:

1. A multi-stage amplifier of the type including a plurality of individually shielded removable interstage coupling elements, each coupling element with its respective shield forming an integral unit, and means mechanically interconnecting all of said shielded elements to permit the simultaneous removal of all of said coupling elements from the amplifier, said means including insulating material preventing current flow from one coupling element to another along said mechanical interconnecting means.

2. In a multi-stage amplifier, a removable interstage coupling system comprising a coil element for each stage of said amplifier, a metallic coil can supporting and shielding each of said coil elements, terminals for each coil element engaging relatively stationary terminals of said amplifier, and means mechanically securing all of said coil cans to a plate, said means including insulation preventing current flow from one can to another along said plate.

3. In a multi-stage amplifier, the combination with relatively stationary circuit elements including groups of terminals for engagement with cooperating groups of terminals of a plurality of interstage coupling coils, of a coil assembly comprising a coil form for each interstage coupling, coils on said forms, a metallic shield housing and supporting each of said forms, coil terminals carried by each of said forms for cooperation with the respective groups of fixed terminals, and means mechanically connecting said metallic shields to permit the simultaneous engagement of all of said cooperating groups of terminals, said means comprising non-conducting material insulating said shields from each other.

4. In a radio receiver, the combination with a casing having an opening in one wall, of a closure for said opening, a plurality of coupling coil shields and means for mounting the shields on said closure, each of said means including a pair of insulating plates disposed on opposite sides of one end wall of each of said shields, a rivet extending through said plates and insulated from said shields whereby said shields are insulated from one another.

5. A removable coil assembly for a multi-stage amplifier comprising a plurality of coil units, a shield can for each coil unit, each of said coils with its respective shield forming an integral unit, a supporting plate, and means supporting all of said shield cans on said plate and insulating said cans from each other.

6. The invention as set forth in claim 5, wherein in said plate is metallic; and said supporting means includes strips of insulating material between each shield can and said plate, rivets insulated from each can for securing said strips to the respective cans, and screws threaded into said rivets to secure the cans to said plate.
